(57) **CLAIM**

The ornamental design for a portion of a light-emitting diode, as shown and described.

DESCRIPTION

FIG. 1 is a front perspective view of a portion of a light-emitting diode, showing our new design;
 FIG. 2 is a rear perspective view thereof;
 FIG. 3 is a front elevational view thereof;
 FIG. 4 is a rear elevational view thereof;
 FIG. 5 is a top plan view thereof;
 FIG. 6 is a bottom plan view thereof;
 FIG. 7 is a right side elevational view thereof;
 FIG. 8 is a left side elevational view thereof;
 FIG. 9 is a front perspective view of a portion of a light-emitting diode of FIG. 1; and,
 FIG. 10 is a rear perspective view of a portion of a light-emitting diode of FIG. 1.
 The broken line showing of the remainder of the light-emitting diode is for illustrative purpose only and forms no part of the claimed design.
